UNITED STATES PATENT OFFICE.

JOHN R. KELLER, OF GLENSHAW, PENNSYLVANIA.

DESIGN FOR A BOWL OR SIMILAR ARTICLE.

Application filed April 22, 1924. Serial No. 9,353. Term of patent 7 years.

To all whom it may concern:

Be it known that I, JOHN R. KELLER, a citizen of the United States, residing at No. 2 Spencer Lane, Glenshaw, county of Allegheny, State of Pennsylvania, have invented a new, original, and ornamental Design for a Bowl or Similar Article, of which the following is a specification, reference being had to the accompanying drawing, forming a part thereof, the figure being a perspective view of a glass dish showing my new design.

I claim:

The ornamental design for a bowl or similar article substantially as shown.

JOHN R. KELLER.

Witnesses:

JOHN F. WILL,
VERNA B. NELSON.
